UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

BROADCASTING SYSTEM.

Application filed October 6, 1923. Serial No. 667,024.

To all whom it may concern:

Be it known that I, EDWARD E. CLEMENT, a citizen of the United States, residing at Washington, in the District of Columbia, have invented certain new and useful Improvements in Broadcasting Systems, of which the following is a specification, reference being had therein to the accompanying drawing.

10 My invention relates to broadcasting systems. For a completely organized system of this kind there are a number of essentials to be considered which have not yet been rendered available in pure radio transmission to my knowledge. Among these are, secrecy or restriction of the service to those alone who pay for it; uniformity and continuity of service equal at least to those possible in standard wired systems; efficiency in transmission and fidelity in reproduction; testing, control, metering and supervision of the service from a central point. It will be observed that these requisites of good service call for means of both distributive and selective character, that is to say, means for distributing the broadcast program or communications to all consumers in common, and means for individualizing each consumer for any purpose when necessary. It is the object of my invention to supply these means by superposing an organized broadcasting system as a phantom upon a combination of existing wired systems, and without interfering with the ordinary functions of said wired systems, to utilize their characteristic forms and arrangement for the appropriate guidance, distribution and control of modulated high frequency or carrier current waves as well as direct and alternating current supply, and the like. Such wired systems are already divided by the nature of their respective services into two general classes, distributive systems, including electric light, power and telegraph circuits and some many-party telephone circuits; and selective systems, including telephone exchange systems and all others that have individual wires leading to the subscribers or consumers.

50 I attain my object by combining in use these two classes of systems, connecting transmitting and receiving stations to both, i. e., to the electric light or equivalent network on one side and to the telephone line wires on the other. By this means all the re-

ceiving or subscribers' stations are accessible in common for broadcasting over the common or distributive medium, and each station is also accessible individually over the telephone circuit allotted to it, or to 60 which it is allotted. In building up a complete system so as to organize on an interstate or national scale, this arrangement contemplates regional distribution, i. e., distribution in territorial districts local in character, such as a city or a county, and relaying from the national or inter-national sending stations through the regional or district centers to the local subscribers. The general broadcasting may be by any known or suitable means either pure radio or combinations of wire and radio transmission, to which broadly I lay no claim herein. In the present case for simplicity I assume pure radio for all primary station broadcasting, the 75 principal usefulness of my combination of wire systems being in the final distribution to subscriber-consumers.

55 My invention is illustrated as to one form in the accompanying drawings, in which:

Fig. 1 is a schematic diagram indicating the layout of a general system having high power primary broadcasting stations and relayed local or regional distribution;

60 Figs. 2 and 2^a taken together show some detail of the circuits and connections in the local or regional distribution area, also a metallic circuit metering scheme.

65 Referring to Fig. 1, 1, 2 and 3 represent telephone subscribers' stations, connected by wires 4, 5 and 6 to the central telephone exchange C, and all assumed to be supplied with electric light current over a common wire network indicated at 200, from a central station 7. Superposed upon these two 90 wire systems is a broadcast distribution system having a central station R fully equipped with switchboards and a line radio or Squier transmitter for broadcasting over the wire network 200, with which it is connected as indicated at 208. This station R is also equipped with receiving and relaying apparatus for different wave lengths, and has access to all lines in the telephone system through the exchange 7, as indicated 95 by trunk wires 15. Associated with the telephone subscribers' stations 1, 2, and 3, are broadcast receivers 1^a, 2^a and 3^a, each physically connected on one side by wires 1^c, 2^c, or 3^c to the electric light circuit 200, and on 100

100

105

110

the other side by wires 1^b, 2^b or 3^b to an individual telephone line 4, 5 or 6.

In operation, messages or programs broadcasted by means of wave radiation from primary stations as 12, 13 and 14 are received at the regional central station R and relayed through the Squier transmitter by means of guided waves or modulated carrier current over the net work 200 to all the local stations as 1^a, 2^a and 3^a in common, the service being supervised, controlled and metered over the individual telephone lines as 4, 5 and 6. Instruments 1^a, 2^a and 3^a are standardized and adjusted to one wave length, so that little or no local tuning is required, all tuning being done at the central station 8, the operator there being able to listen in on the local subscribers' receiving instruments over the telephone wires, and to determine thereby the correct adjustment of transmitted wave length.

In addition to relaying messages received by radio waves from primary stations, the central station 8 is equipped with local modulating and Squier transmitting apparatus, for originating programs and distributing the same over the network 200; and in this connection there may also be provided trunk or long distance telephone wire connections for bringing in news, communications or programs from distant points by wire and relaying them out over the local area through the Squier transmitter. I lay no claim to this use of long distance telephone wires per se, but consider the use of the same in combination with the network 200 and the local individual telephone wires as 4, 5 and 6, to be within the scope of my invention, as creating an alternative all wire system which can be depended upon for maintaining continuity of important service when static or other conditions make the receipt of radiated waves from primary stations uncertain.

Referring to Figs. 2 and 2^a, I have therein shown circuits of the central office and substation equipments and connections, Fig. 2 representing the telephone side of the system, and Fig. 2^a the broadcasting side of the system. Before proceeding to detail description it may be noted that in accordance with standard telephone practice, provision is made for keeping the telephone lines and central office circuits clear of all grounds or other disturbing connections during conversation. When the broadcast receiver goes into service, by closing the filament switch its operation in receiving is identical with that of any similar receiver. Each set is provided with a cut off relay energized when the telephone set goes into commission, either by calling or being called, and at the central office whenever the broadcast operator takes control of the line, he disables it in the usual manner by pulling

up the cut off relay at the telephone switchboard, this however being subject to the condition that a special tone test may be put on, so that all operators may know that the line is held on the broadcast board, and subject to interruption for telephone connection. I prefer to use this tone test only with the broadcast operator's testing plug, because his regular connecting plug includes within its functions that of connecting a subscriber through the station amplifier to the broadcasting transmitting set, and a connection of this character should not be interrupted without permission.

Referring particularly to the diagram, Fig. 2, A and A' are two subscribers' stations connected by line wires 16-17 and 18-19, respectively, to the central station C where they terminate on jacks J and J'. P-P' are plugs forming the terminals of a cord circuit 20-21, 22-23, having a bridged repeating coil I², ringing and listening keys k and k', supervisory signals s-s' and bridging connection to the main battery B. The same battery is shown supplying current to the line relays L, L', and through contacts of the cut off relays L², L³ to the respective lines for calling purposes. In this system, when a subscriber takes down his receiver, the line relay lights its lamp, which is extinguished when the operator inserts the answering plug.

The circuit of the line relay, for example, relay L', may be traced from battery B through the left hand winding of L, left hand contact of L², sleeve line 19, wires 19-19^a, through L⁴ (Fig. 2^a), subscriber's telephone set, line 18, right hand contact of relay L³, right hand winding of L' back to grounded side of battery B. Battery supply for the connected lines is thereafter taken through the cord circuit 20-22, 21-23, in a manner well understood in the art. When the substation telephones are out of service, with their receivers hanging on their hooks, the line circuits are conductively open for direct current, leaving the ringers Q and Q' in circuit for alternating ringing current passing through the condensers q-q'.

Referring now to Fig. 2^a, it will be observed that the broadcast switchboard which I have designated generally by the letter R, is connected to the subscribers' lines by multiple taps marked 16^a, 17^a, and 17^b, and 18^a, 19^a, 19^b. These terminate on multiple jacks J², J³, corresponding to the multiple jacks on the telephone switchboard. It should be noted that throughout this system the tip wires 16 and 18 with their branches are connected to ground, while the sleeve wires 17 and 19 and their branches, are connected to battery. This is extended into the broadcast side of the system for the purpose of securing proper balance between the main battery or power plant of that side and

the main battery or power plant of the telephone side of the system.

At the subscribers' stations taps are also taken off from the telephone terminals to the broadcast receiver terminals as indicated at 18^c, 19^c, and 19^d. (The receiver is shown only at one substation for sake of simplicity of illustration.) The two branches 19^c and 19^d are taken from the sleeve or battery side 10 of the line 19, and are connected to opposite terminals of the winding of a relay L⁴, which constitutes the substation cut off relay for the broadcast receiver. The winding of this relay is bridged by a condenser q² 15 through which both ringing and voice currents can pass without substantial impedance. Where the broadcast receiver is attached to a party line substation, this relay L⁴ may be omitted, since on such party lines 20 there are usually grounds on one side or the other.

Normally, that is to say when the telephone circuit is not in use, the cut off relay L⁴ is deenergized and as a consequence the wire 19^c is connected through a back contact of the relay through extension wire 24 to the branch 25 connected to the "A" battery marked A² in Fig. 2^a. The wire 18^c similarly passes through a back contact of the relay to the extension wire 26 leading to test or listening relay L⁵ and ground. 18^c, it will be remembered, leads to the tip or ground side of the line, therefore it is the side which in the broadcasting can be made 30 use of with a permanent ground or grounds, without disturbing the balance of the telephone circuit.

The broadcast receiver at the substation A' is shown as comprising an input connection 28 (from the electric light network 200,) a tuned coupler 29, detector tube 30, audio amplifier tubes 31 and 32, and the usual transformers 33, 34, 35, the last mentioned transmitting the amplified audio waves to 45 the telephone receiver or loud speaker 36. The filament battery is A². The plate battery is B² and suitable tuning condensers and coils, tickler coil for regenerative effects, etc., are provided as required. I should 50 remark in passing that this representation of the radio receiver is intended to be typical only. The present invention does not concern itself specifically with the design of the local broadcast receiver sets, and other 55 circuits and apparatus may be substituted for those shown in the diagrams without departure from the invention.

The relay L⁵ has four pairs of contacts, one pair 27^a closing the wires 25 and 37 60 from battery A² to the filaments. The second pair 27^b closes the wires 25 and 38 so as to put battery A² on the transmitter T', and through the induction coil winding I, to ground. The third and fourth pairs of contacts 27^c, 27^d, close the wires 39 and 40, form-

ing terminals of the secondary induction coil winding I', to the tip and sleeve side of the telephone line respectively, through the back contacts of relay L⁴. The transmitter T' is shown hanging upon a hook switch H' 70 controlling the connection of wires 41 and 42, constituting a parallel link between the battery A² and the filament bus 43. Thus the filament can be heated and the broadcast receiver put in service either 75 through the agency of the relay L⁵, or by the switch hook H'. The former is controlled by the broadcast operator at central, and the latter by the subscriber at the substation. In addition to the hook, the subscriber has a manual switch h by which he can connect the battery wire 42 through a wire 44 to his transmitter T', coil and ground, so as to energize his talking circuit. I provide an ordinary telephone receiver t' in series with the secondary of the induction coil I', and I interpose a pair of condensers q³, q⁴ between the secondary of the induction coil I' and the telephone receiver t' on the one hand, and the terminals 90 of relay L⁵ on the other, so that while the subscriber by means of switch h can connect his telephone T'-t' for receiving calls over the telephone line, he cannot originate calls 95 thereover from the broadcast receiver extension.

Returning now to the central station, and particularly to the broadcast department thereof shown in Fig. 2^a, T represents a Squier broadcasting transmitter, symbolized 100 in a very simple form, but supposed to contain the usual elements and connected on the output side with the electric light or power network 200. This connection includes suitable devices, known in the art, to exclude high voltage and low frequency currents, surges, hum, etc. Suitable switches are assumed located at a convenient point. The jack J⁴ connected to the amplifier t² 105 and thence to the transmitter T, symbolizes 110 a group of such jacks or equivalent connecting means such as automatic switches, controlled by dials or keys, for connecting any of the wire lines to said transmitter. Detailed appliances, for receiving radio messages from primary centers, for the switching, and for the local broadcast transmission, 115 are well known in the art, and need no specific description in this specification.

The cord circuit between plugs P² and P³ 120 in Fig. 2^a is the same as the operator's cord circuit, in Fig. 2, but the broadcast operator also has special test cords such as that shown in the upper part of the figure connected to plug P⁴. Here the keys K-K' are of standard construction, as in the other cords, and the test contact of the plug P⁴ is connected through suitable resistance to the supervisory lamp s² to the broadcast battery B', means 125 such as the commutator p⁵ being provided 130

to give special tone test on the test thimbles of the multiple jacks J, J', J², etc. It will be observed that the constant connection of the sleeve or battery wire 24 at the radio-
5 phone substation to the bus wire 25 of the battery A², produces charging of that battery by the constant flow of current there-
through from the main radio battery B' at the central office. This charging circuit
10 may be traced from battery B' through contact of relay L⁷, wire 19^a, 19, 19^c, contact of relay L⁴, 24, A', and through "natural" ground back to battery B'. The amount of energy thus delivered to the battery A² de-
15 pends upon the size of the line wires, and the length of time available for such charging. As shown, the battery wire 24 is not cut off except when the cut off relay L⁴ pulls up which is only when the line wire
20 is in use for conversation. With No. 19 line wires, and using only the sleeve wire for conduction, it would be possible to safely transmit from one-half ampere to two or three amperes, according to the line resist-
25 ance and the voltage of the battery employed. Where this voltage is standard manual tele-
phone voltage, say 22, and the single wire resistance to the substation is from 25 to 50 ohms, it would be possible to maintain the
30 battery A² continuously charged, provided the time of discharge be not too long ex-
tended, and the charging be not interrupted by other contingencies, such as the excessive telephone use of the line.
35 I wish to point out in connection with this, that the art has progressed to a point where filament current required is so small that it is well within the limits of the am-
perage permissible over the smallest tele-
40 phone wires, even continuously flowing, and therefore direct feed of the filaments over the telephone wires is not only possible but, for reasons that will be plain to those skilled in the art, will be the best practice. It is
45 also possible with instruments now well known to supply filament current from electric lighting circuits, and both these methods of feed are within the scope of the present invention, owing to my combination of these
50 wires into one system.
For metering the subscriber's radio service at the central station, an impulse meter which may be of the standard type as indicated diagrammatically at 50 (Fig. 2) or
55 any known or other suitable type capable of recording current impulses or circuit closures is employed. This meter is ar-
ranged to have its energizing circuit closed through a normally open contact 51 of a
60 relay 52 actuated conjointly with the line lamp L', which in the present case is the usual night alarm relay. For actuating the meter 50 from the subscriber's broadcast receiving station at substantially constant
65 time intervals, a meter actuator in the form of an intermittent circuit closer of any known or other suitable type is provided. In the present arrangement this actuator 53 is shown as an intermittent thermal switch of the type used as sign flashers. The energizing circuit of the actuator 53 including the winding 54 and contact 55 is connected with the electric light circuit 200 through a normally open contact 56 on the broadcast receiving station switch hook H', while the circuit closing contact 57 is connected in shunt of the subscriber's telephone-transmitter circuit-switch-hook-contacts, so that upon closure they will effect a closure of the line circuit in the same manner as when the subscriber's telephone receiver is raised except that the closure is momentary or brief and not continuous.
Thus when the radio receiver is in use the switch-hook H' being in raised position
70 maintains the contacts 56 closed which maintain closure of the energizing circuit of the actuator 53 which circuit may be traced from the lower conductor of the power circuit through conductor 58, winding 54, contact 55, conductor 59, contact 56, conductor 60 back to the upper conductor of the power circuit. This causes the actuator 53 to warp back and forth and intermittently open and close its own circuit in a manner well understood, which causes the contact 57 to be intermittently actuated to momentarily close the line circuit at the subscriber's end over the following path: Contact 57, conductor 61, switch-hook contact a, line wire 18, line
75 wire 19, switch-hook b, conductor 62, back to contact 57. Each momentary closure of the subscriber's line circuit effects an actuation of the line relay L' in the usual manner as when calling, except that the actuation is momentary; which in turn effects an actuation of the meter 50 through relay 52 and its contact 51. The circuit of relay 52 may be traced from battery B, through winding of
80 relay 52, line lamp and contact of line relay L' back to the grounded side of battery B. The circuit of meter 50 may be traced from the free or upper side of battery B through contact 51 of relay 52, winding of meter 50 and back by way of ground to the grounded
85 side of battery B. The meter 50 as shown is a standard Western Electric line meter of a type in common use. It has a high resistance winding 50^a and a low resistance winding 50^b, which causes it to operate as follows: When circuit is first closed through the high winding 50^a, the meter 50 is energized quickly to pull up its armature and close the circuit of the low resistance or working winding 50^b. A rush of current flows through this low winding, which then
90 actually turns the ratchet wheel of the meter. This could be replaced by any suitable magnetically actuated counting device which would respond to closure of its circuit at
95

the contact 51 of relay 52. Thus, as long as the broadcast receiving station is in use, the meter 50 is actuated at substantially constant recurring periods proportionate in number to the time the receiving station is in use. It is to be noted that while the meter 50 will be actuated once each time the subscriber closes his line circuit in initiating a telephone call, and that it will not continue to record the time of use of the radio receiver during use of the telephone substation, there will however be no unfairness in the broadcast service charge due to the fact that, in practice, the suspension of metering during use of the telephone substation will substantially compensate for the extra actuation of the meter at the initiation of a call.

As stated above, an intermittent circuit closer of any suitable type may be used in place of the meter actuator 53, for example any kind of an electrically operated motor of fairly constant speed may be used to effect the momentary closure of the telephone line circuit.

A number of modifications in the system thus specifically described can be made without departure from the scope of the invention. For carrier current transmission purposes, as an all metallic circuit is preferable, the telephone circuits, regarded as a network, or any one telephone circuit, may be used as one side of a phantom broadcasting circuit, and the electric lighting network 35 may be used as the return side of the circuit. In such case, proper arrangements of condensers or filters at the central broadcasting station and the subscribers' stations should be employed, in a manner well understood 40 in the art, to prevent any ground leakage, or any communication from grounds on the electric lighting network to the telephone circuits. As a further modification, some or any of the telephone circuits may be used 45 for outward transmission of the broadcast currents from central to the subscribers' receiving instruments, and another telephone circuit or circuits may be used as the return. In such case, the subscribers' stations would 50 have access on one side to the going circuits, and on the other to the return circuit or circuits, and as transmission on any particular wave length would be common as to any 55 particular group of subscribers, inductive effects can be neglected.

Such modifications do not interfere with the ordinary electric energy feed (battery) over ordinary telephone circuits is usual, but on the contrary permit full use to be made 60 of the following combination, which I believe to be novel: (1) energy feed over ordinary telephone circuits as usual, (2), outgoing transmission of filtered wave bands over the telephone circuits, (3) return of 65 wave bands over common return wires,

which may be other telephone circuits. The supply of current energy to the subscribers' stations permits local supply of carrier current component at the subscribers' instruments with a minimum of complication.

70

I claim:

1. In a broadcasting system the combination of a current distributing system comprising a connected net work of wires serving a given area, a communication system composed of separate individual wires, subscribers' stations in said area provided with carrier current receiving apparatus, connections from said subscribers' receiving apparatus to said distributing system for receiving waves broadcasted thereon, other connections from said subscribers' receiving apparatus to said individual wires for individually receiving and transmitting electrical impulses or waves thereover, and a central broadcasting station connected for transmitting to said distributing system of wires, and also having access to said individual wires for communication thereover with the individual subscribers' stations.

75

2. In a broadcasting system, a current distributing net work of wires, serving a plurality of consumers' stations in common, a telephone exchange system having separate wired circuits leading to subscribers' stations, a plurality of broadcast subscribers' stations having broadcast receivers connected to said distributing net work for common service thereover and individually connected to telephone circuits for individual communication thereover, and a central broadcasting station with transmitting apparatus connected to said distributing net work and having access to said telephone circuits for individual communication with 100 said subscribers' stations.

80

3. In a broadcasting system, a central broadcasting station equipped with transmitting apparatus, and with ancillary testing, control, metering and supervisory apparatus, a plurality of subscribers' stations each having a broadcast receiving set, a common wire connection from the central broadcasting transmitter to all such subscribers' receiving sets in common and individual wire connections from the ancillary apparatus at the central station to the subscribers' receiving sets for joint control thereof.

85

4. In a broadcasting system, a central broadcasting station and subscribers' stations served therefrom, in combination with a wired system adapted to serve a plurality of stations in common, a second independent wired system adapted to serve subscribers' stations individually, receiving apparatus at each subscriber's station operatively connected with both said wire systems, and means at the central broadcasting station for transmitting over the first wired system 125 to subscribers' stations in common and for 130

- communicating individually with said subscribers' stations over the second wired system.
5. In a broadcasting system, a central broadcasting station and subscribers' stations served thereby in combination with a common wired broadcasting circuit or network connecting the central station with the subscribers' stations, individual wires connecting said central station with the respective subscribers' stations, and a broadcast receiving set at each subscriber's station electrically connected on one side to said wired broadcasting circuit and on the other side to its individual wire circuit for joint operation thereby.
6. In a broadcasting system, a central broadcasting station and subscribers' stations served therefrom, in combination with a wired power distributing net work and a wired telephone exchange system, with a broadcast receiving set at each subscriber's station affording communication between said central station and the subscribers' stations over said net work in common, and over said telephone system individually, said sets being irresponsible to ordinary currents carried on said net work and said wires respectively.
7. In a broadcasting system, a central broadcasting station and subscribers' stations served therefrom, in combination with a wired power distributing net work and a wired telephone exchange system, with unitary means at each subscriber's station affording communication between said central station and the subscribers' stations over said net work in common, and over said telephone system individually, and other means to prevent interference between the currents or waves thus employed in broadcasting and communicating between the central station and the subscribers' stations, and other currents or waves normally employed over the said net work and the said telephone system respectively.
8. In a broadcasting system, the combination of a wired electric light net work and a telephone exchange system, with a broadcasting central station and subscribers' stations having combined broadcast receiving and telephone sets served by said central station, said central station and subscribers' sets being interconnected through both said net work and said telephone system.
9. In a broadcasting system, primary transmitting centers, regional relaying and distributing centers, a plurality of receiving stations associated with each regional center, common wire connections therefrom to said regional centers, and separate individual wire connections therefrom to said regional centers, and unitary means at each receiving station operatively connected with both said common and said individual-wire connections for communication from and to its regional center.
10. In a broadcasting system, a current distributing net work, of wires, serving a plurality of consumers' stations in common, a telephone exchange system having individual wired circuits leading to subscribers' stations, a plurality of broadcast subscribers' stations each having a combined broadcast receiver and telephone set connected on one side to said distributing net work, and on the other side to its individual telephone circuit, and a central broadcasting station having carrier current transmitting apparatus and telephonic transmitting and receiving apparatus, said carrier current transmitting apparatus connected to said distributing net work for broadcasting thereover and said telephone apparatus connected to said telephone circuits for complete metallic circuit communication with said subscribers' stations.
11. In a broadcasting system, a central broadcasting station equipped with carrier current transmitting apparatus, and with ancillary electric current supply apparatus, a plurality of subscribers' stations equipped with receiving apparatus served from said central station, a common wire connection from the central broadcasting transmitter to all such subscribers' stations, individual wire connections from the ancillary apparatus at the central station to the subscribers' stations, and means operatively connecting said receiving apparatus with said individual line whereby signals sent from said transmitting apparatus over said common wires may be sent back over said individual wires.
12. In a broadcasting system, a central broadcasting station equipped with carrier current transmitting apparatus, and with ancillary electric current supply apparatus, a plurality of subscribers' stations equipped with receiving apparatus served from said central station, a complete signal transmission wire connection from the central broadcasting transmitter to all such subscribers' stations in common, individual complete signal transmitting wire connections from the ancillary apparatus at the central station to each of the subscribers' stations, and means whereby said transmitting apparatus may be caused to transmit signals out over said common wire connection and back over any of said individual wire connections and other means at the subscribers' stations to take electric current energy over said individual wires for the operation of said receiving apparatus.
13. In a broadcasting system, a central broadcasting station and subscribers' stations having broadcast receivers served therefrom, in combination with a wired sys-

tem adapted to serve a plurality of said stations in common, and a second independent wired system adapted to serve subscribers' stations over individual wire connections, 5 said broadcast receivers having their input and output ends connected respectively to the common wire connection and their respective individual wire connections and means at the central broadcasting station for 10 transmitting signals to subscribers' stations over one of said wired systems and for receiving signals from said subscribers' stations over the second wired system.

14. In a broadcasting system, a central 15 broadcasting station and subscribers' stations served therefrom, in combination with a wired power distributing net work and wired telephone exchange system, with means affording communication between 20 said central station and the subscribers' stations over said net work and over said telephone system as independent signaling channels in series, said means being irresponsible to ordinary currents carried on said 25 net work and said wires respectively.

15. In a broadcasting system, a central broadcasting station and a plurality of subscribers' stations having broadcast re-

ceivers, all metallic wired circuits extending between said subscribers' stations and 20 said central station, and a carrier current transmitting apparatus at said central station, with means to connect the same and the subscribers' receivers to a metallic circuit as one side of a phantom broadcasting circuit, and to another metallic circuit as the 25 other side or return wire thereof.

16. A carrier current distribution system comprising a central station and a plurality of subscribers' stations, a plurality of wired 40 circuits connected to said central station, carrier current transmitting apparatus at said central station, carrier current receiving apparatus at said subscribers' stations, means for supplying electric energy feed to the subscribers' stations over 45 said circuit, means for transmitting modulated carrier currents over some of said circuits to said subscribers' stations, and means to return said carrier currents over 50 other of said circuits to said transmitting apparatus.

In testimony whereof I hereunto affix my signature.

EDWARD E. CLEMENT.
